UNITED STATES PATENT OFFICE.

WILLIAM McCONNELL MATHES, OF GATESVILLE, TEXAS.

MEAT-CHOPPER.

SPECIFICATION forming part of Letters Patent No. 313,356, dated March 3, 1885.

Application filed May 21, 1884. (No model.)

To all whom it may concern:

Be it known that I, WILLIAM McCONNELL MATHES, of Gatesville, Coryell county, in the State of Texas, have invented a certain new and useful Improvement in Meat-Choppers, of which the following is a full, clear, and exact description, reference being had to the accompanying drawings, forming part of this specification.

10 This invention relates to a machine for either tendering or mincing meat. It is for hand use, and automatically changes the position of the meat beneath the vertically-reciprocating knife or tendering-blade.

15 Figure 1 is a side view. Fig. 2 is an end view. Fig. 3 is a top view. Fig. 4 is a vertical section at 4 4, Fig. 3. Fig. 5 is a detail transverse section showing a tendering blade or device secured to the sash in place of the 20 knife.

25 *a* is the frame of the machine. *b* is the movable carriage or meat-board carried between supporting-rollers *c* and steady-rollers *d*. Beneath the meat-board are two racks, *e*, whose teeth engage pinions *f* upon a shaft, *g*, that carries at its end a spur-wheel, *h*. *i* is a hand-crank, whose shaft *i'* carries a spur-wheel, *j*, that engages with the wheel *h*, and a spur-wheel, *j'*, that engages with a pinion, *k*, upon 30 a crank-shaft, *l*, by which the sash is actuated. The crank *m* of the shaft *l* is connected by a pitman or rod, *n*, with the sash *o*. The sash works vertically in guides *p* of the frame *a*. The sash is formed for the attachment of the 35 knife or tenderer *r*.

40 I propose to secure the blade to the sash in the following manner: *s* is a horizontal tongue of the sash, that fits in a groove, *t*, of the blade, so as to prevent all vertical movement of the blade upon the sash. The blade *r* is held firmly upon the tongue by clips *u*, held by screws *v*.

45 *w* are wires or rods extending across the machine parallel to the knife or tendering-blade *r*. These wires or rods are movable, so that they may be arranged in close proximity to the sides of either the knife or tendering-blade. As the former is thinner than the latter, it is obvious that the rods or wires would require 50 to be movable for the purpose stated. The office of these wires is to prevent the blade *r* from carrying the meat upward with it as it ascends. The wires or rods *w* have heads

at one end and at the other end are drawn outward by the thumb-screws *y*. The wires 55 are secured in horizontal slots *x* at each end, giving the described adjustment, and when drawn tight by the thumb-nuts are thus held in position.

55 The operation of the machine is as follows: 60 The meat—as a steak after removal of bones—is laid upon the movable table or board *b* and the crank *m* turned. This causes the meat-board to pass beneath the blade, and at the same time causes the vertical reciprocation of 65 the sash and knife or blade *r*. The knife may have sufficient depth to cut down to the board, and thus mince the meat. On the other hand, a knife of less depth will not cut the meat quite through, so as to merely score the meat. 70 The depth of cut would thus depend on the depth of the knife.

75 When it is preferred to bruise the meat, instead of scoring or cutting it, a plain or serrated blade or bar, *r'*, is used in place of the knife *r*, (see Fig. 5,) the wires or rods *w* being set a sufficient distance asunder to admit the passage of the tendering-blade between.

80 It will be seen that by the oscillation or rotation of the hand-crank any part of the meat 80 may be brought beneath the sash and operated upon as much as may be desired.

85 The relative speed of movement of the sash *o* and meat table or board may be regulated by changing the spur-wheels for others of different size. Thus the spur-wheel *k* may be changed for one larger and wheel *j* for one smaller in diameter than shown to decrease speed of the sash.

90 I claim as my invention—
1. The combination of the frame having horizontal slots *x*, a sash having interchangeable cutting and tendering blades, devices for operating the sash, and wires or rods *w*, adjustable in said slots to accommodate either 95 blade, as set forth.

95 2. The combination of shaft *i'* with spur-wheels *j*, *j'*, pinion *k*, crank-shaft *l*, pitman *n*, sash *o*, removable blade *r*, shaft *g*, carrying spur-wheel *h* and pinions *f*, and meat board 100 or table *b*, with racks *e*, substantially as and for the purpose set forth.

WM. MC. MATHES.
